DESCRIPTION

[52] U.S. Cl. D34/30
[58] Field of Search D34/28, 30; 198/338,
198/335

FIG. 1 is a right perspective view of a pair of escalator control boxes showing our new design;
FIG. 2 is a left perspective view thereof.
The broken lines show the environment, an escalator terminal, in which the pair of escalator control boxes are placed and form no part of the claimed design.

FIG. 1
